(57) **CLAIM**

The ornamental design for a sports simulation trainer, as shown and described.

DESCRIPTION

FIG. 1 is a perspective view of a sports simulation trainer showing my new design;
 FIG. 2 is another perspective view thereof;
 FIG. 3 is a front elevational view thereof;
 FIG. 4 is a rear elevational view thereof;
 FIG. 5 is a left elevational view thereof;
 FIG. 6 is a right elevational view thereof;
 FIG. 7 is a top plan view thereof;
 FIG. 8 is a bottom plan view thereof; and,
 FIG. 9 is a perspective view of the sports simulation trainer in an alternative state.
